US0D1046853S

(12) **United States Design Patent** (10) **Patent No.:** **US D1,046,853 S**
(45) **Date of Patent:** **** Oct. 15, 2024**

(54) **DISPLAY**

(71) Applicants: **Toshihiro Hamamura**, Tokyo (JP);
Goro Katsuyama, Tokyo (JP)

(72) Inventors: **Toshihiro Hamamura**, Tokyo (JP);
Goro Katsuyama, Tokyo (JP)

(73) Assignee: **Ricoh Company, Ltd.**, Tokyo (JP)

(**) Term: **15 Years**

(21) Appl. No.: **29/865,248**

(22) Filed: **Jul. 15, 2022**

(30) **Foreign Application Priority Data**

Feb. 8, 2022 (JP) ..... 2022-002397 D

(51) **LOC (14) Cl.** **14-02**

(52) **U.S. Cl.**

USPC **D14/341**
